UNITED STATES PATENT OFFICE

2,128,780

AIRPLANE PROPELLER

Michael Leff, Buffalo, N. Y., assignor of one-half to Lawrence C. Lake, Kenmore, N. Y.

Application December 20, 1937, Serial No. 180,739

3 Claims. (Cl. 170—165)

This invention relates generally to propellers but more particularly to a propeller designed for use on airplanes and other aircraft.

It has for one of its objects to provide a propeller of this character which is so designed and constructed as to create a maximum pulling and lifting power with a minimum of slippage.

Another object of the invention is to provide an airplane propeller whose blades are so disposed and shaped as to effectually cut into and grip the air to develop greater power efficiency and propulsive and lifting effort.

A still further object of the invention is to provide a dual bladed construction wherein a plurality of pairs of blades are disposed substantially radially about the axis of rotation in predetermined spaced relation and of such shape as to afford efficient operation.

In the accompanying drawing:—

Figure 1 is a perspective view of the propeller embodying my invention. Figure 2 is a side or edge view thereof. Figure 3 is an end view of the same. Figures 4 and 5 are cross-sections taken substantially in the plane of the correspondingly numbered lines in Figure 1.

Similar characters of reference indicate corresponding parts throughout the several views.

Referring now to the drawing, 10 indicates the hub of the propeller which is adapted for attachment in the usual way to the motor shaft of the airplane or other aircraft. Radiating from this hub are a plurality of pairs of propeller blades 11, 12, there being two of such pairs shown in the drawing disposed at the diametrically opposite sides of the hub. The blades 11, 12 of each pair are disposed side by side axially of the hub 10 in substantially parallel spaced relation to provide a comparatively narrow air space 13 between the companion blades. The diametrically-opposed pairs of blades are set at a substantially acute angle to their plane of rotation, with the pair of blades at one side of the hub-axis pitched or partially spiraled in one direction and with the pair of blades at the opposite side of such axis similarly pitched in the reverse direction. By this general dual blade arrangement, as the propeller revolves the blades effectually cut into and grip the air to develop a maximum lifting and propulsive power.

The blades of each pair are symmetrical and are of such shape and contour as to effectually cut through the air and at the same time guide and direct the air in such a way as to not only exert a greater pulling and lifting power but reduce to a minimum any tendency of the plane

to skid or side slip. To this end, and by preference, the blades 11 and 12 of a pair are substantially the same shape in elevation or plan contour, and as seen in Figures 1 and 3, the leading edge of the front blade 11 is disposed slightly forwardly relatively to the corresponding edge of the rear blade 12 and the leading marginal portion of the former is slightly preferably shaped at its front side in the manner indicated at 14, while its rear side is convexly curved as indicated at 15 whereby this blade effectually cuts into the air and directs it against the opposing wall of the rear blade and into the space between such blades. The trailing marginal portion of the front side of the front blade 11 is likewise preferably shaped as indicated at 16, and its trailing edge terminates forwardly of the corresponding edge of the companion rear blade. This rear blade 12 of each pair is preferably dished or concave on its rear side and the contiguous marginal portion thereof is convex, as indicated at 17 to provide a leading edge for such blade which will effectually cut into the air. The trailing marginal portion of the front side of the rear blade 12 is convexly curved, as indicated at 18, and by thus shaping the blade, as the propeller revolves in counter-clockwise direction viewing Figures 1 and 3, the front blade cuts into and effectually directs the air into the space between the companion blades of a pair 30 with both blades screwing through the air to develop a maximum pull, while the rear blade effects the proper displacement of the air rearwardly to provide a maximum lifting effort.

As seen in Figure 1, each blade of a pair is substantially S-shaped in plan, including an inner, radial attaching shank 19 projecting outwardly from the hub 10 and merging into a laterally offset wider or broad section 20 which forms the main body and air-gripping portion of the propeller. This wider section of each blade extends generally backwardly and obliquely to the radial and converges in an outward direction, terminating in a reversely-bent or curved tip portion 21 whose free end is located substantially in the radial plane of the attaching shank 19. By thus shaping the blades, in combination with the dual blade construction, the pocketing and compressing of the air as well as its displacement is effectually regulated and controlled to provide for maximum pulling and lifting power. Furthermore, any tendency to slip or skid is effectually resisted and reduced to a minimum.

I claim as my invention:—

1. An airplane propeller, comprising a hub, and a plurality of pairs of blades radiating from said hub, the blades of each pair being disposed side by side axially of the hub to provide a comparatively narrow air pocket therebetween, the front blade of each pair having its leading edge disposed forwardly of the corresponding edge of the rear blade and the trailing edge of said front blade terminating forwardly of the corresponding edge of said rear blade, the rear marginal side of the leading portion of said front blade being convexly curved toward the opposing face of the rear blade and the front marginal side of the trailing portion of said rear blade being convexly curved toward the opposing face of the front blade.

2. An airplane propeller, comprising a hub, and a plurality of pairs of blades radiating from said hub, the blades of each pair being disposed side by side axially of the hub to provide a comparatively narrow air pocket therebetween, each 5 blade including a shank portion, and a comparatively broad body portion merging into a reversely curved tip portion in the plane of such body portion.

3. An airplane propeller, comprising a hub 10 having a plurality of pairs of blades radiating therefrom, each blade including a shank portion and a comparatively broad body portion merging into a reversely curved tip portion, said body portion being laterally offset from said shank in 15 the direction of rotation of the propeller.

MICHAEL LEFF.
